UNITED STATES PATENT OFFICE

IRVEN H. WILSEY, OF CHICAGO, ILLINOIS

EXERCISING AND MASSAGING DEVICE

Application filed July 18, 1929. Serial No. 379,098.

This invention relates generally to exercising and massaging devices and more particularly has reference to that type of device which is characterized by the fact that, in 5 operation, the machine is held in the operator's hand and applied directly to the body part to be treated.

The general object of the invention is to produce a portable exercising or massaging 10 machine of a type which is distinctly new and different from those heretofore known, and to this end the invention provides a vibratory device of long and narrow or cylindrical shape having handles at opposite ends adapted to be grasped in the two hands of the operator and by which the device may be rolled or moved back and forth upon the part of the 15 body to be treated.

Another object of the invention is to produce a device of this character which comprises an applicator and means contained 20 therein for imparting a reciprocatory movement to the applicator.

A further object is to produce a machine of 25 this character in which the casing of the machine reciprocates and constitutes the applicator.

A further object is to provide a device comprising two relatively vibratory sections both 30 of which are fashioned to be grasped in the operator's hand so that either section may be held while the other section vibrates.

Another object is to provide a machine comprising a cylindrical casing which constitutes 35 the applicator and means within said casing for imparting vibratory movement thereto, said means having handles projecting from opposite ends of the device and adapted to be grasped by the operator whereby the device as 40 a whole may be moved back and forth with the vibrating casing in engagement with the part to be treated.

Another object is to provide a device comprising a vibratory applicator of rounded or 45 cylindrical shape adapted to be rolled upon the surface of the part to be treated.

Further objects and advantages relating to details of construction and operation of the machine will be understood from the 50 following description taken in connection

with the accompanying drawing, in which:

Figure 1 is a central longitudinal section of a device embodying the invention.

Fig. 2 is a similar section taken on a plane at right angles to the plane of the section 55 in Fig. 1.

Fig. 3 is a transverse section taken on the line 3—3 of Fig. 1.

Fig. 4 likewise is a transverse section taken 60 on the line 4—4 of Fig. 1.

Fig. 5 is a fragmentary detail view showing, in central section, a modified construction of the connection between the inner and outer sections of the device.

In its broad concept the invention contemplates the provision of two sections, one of 65 which is mounted within the other to form a unitary structure. The inner and outer sections are adapted for movement through a limited distance relative to each other, and the inner section carries a motor which is 70 drivingly connected to the outer section for effecting such movement. The outer section is smoothly finished to provide a surface for engaging a part of the body to be massaged, 75 whereby the outer section itself becomes the applicator, or means for transferring vibrations to the body.

Relatively, the outer section is of much 80 less weight than the inner section so that in the normal use of the exerciser the inertia of the inner section holds it substantially stationary, while the outer section is reciprocally driven. It should be understood, 85 however, that the reciprocal strokes produced by the machine will occur so rapidly that the resulting action of the machine is substantially vibratory. Nevertheless the strokes are amply powerful and are of sufficient length to produce a thorough and deep movement of the muscles of the body part engaged thereby.

More particularly describing the invention with reference to the drawing, 10 designates generally an inner section in the form of an elongated frame which is enclosed within a hollow outer member or casing 11. While in the present instance the casing 11 is illustrated as being cylindrical 95 in form, and the frame member 10 of such 100

construction as to fit therein, it will of course be understood that the casing may have any shape or configuration desired, in which event the frame will also be changed in conformity therewith.

For convenience in manufacture and assembly it is preferred that the frame be divided transversely to form two portions 10^a and 10^b, the abutting ends of which are provided with complementary interfitting rabbeted grooves, as shown at 12. The two portions are rigidly secured together in any suitable manner, as by means of a pair of bolts 13 extending between two pairs of transversely extending arms 14 and 15 on the portions 10^a and 10^b, respectively. At either end, the frame carries an end closure 16 for the casing in the form of disk-shaped members having peripheral flanges 17 which extend inwardly into the casing 11 and having a peripheral contour conforming to that of the casing. The end closures 16 may be secured to the frame by means of bolts 18, which bolts may also serve as a means for securing a handle 19 to each end of the frame. Preferably the handles 19 extend outwardly from the frame on the axis thereof, and one of the bolts 18 may be tubular to provide a passageway for an electric cable 20 into the interior of the device.

The disposition and arrangement of the parts, as illustrated in Figs. 1 and 2, is such that the casing 11 is engaged and supported only by the end closures 16, there being a slight clearance between the end closures and the casing to permit relative sliding movement therebetween. Thus, the end closures constitute guides for the casing in the movement of the casing relative to the frame.

The frame 10 supports the driving means for producing the relative movement between the frame and the casing. To this end, the inner portion of the frame portion 10^a is substantially annular to receive and engage the casing of an electric motor 21, the armature shaft 22 of which extends substantially axially of the frame toward the other frame portion 10^b. The motor 21 may be mounted bodily in the frame portion 10^a or, as illustrated in Figs. 1 and 2, the structure may be simplified by utilizing the frame portion 10^a to support certain of the motor parts. Thus, the arms 14 on the portion 10^a, which receive the bolts 13 for securing the two frame portions together, may be employed to mount the brushes 23 (Fig. 2) of the motor, and a bearing 23^a in the frame portion 10^a receives the inner end of the armature shaft 22. The interior of the device may be ventilated to prevent over-heating of the motor by providing a series of apertures 16^b in the end closures 16.

The other frame portion 10^b is provided with a gear housing 24 (see Figs. 1 and 3) which has an open side face, and further is

provided with an axially extending bore which receives an extending end 25 of the armature shaft 22. A worm 26 is mounted within the housing 24 on the end 25 of the shaft 22 for engagement with a worm wheel 27 carried upon a shaft 28 extending transversely of the axis of the frame. The shaft 28 is journaled at one end in a closed bearing 29 rigidly fixed in a bore 30 formed in the side wall of the housing 24. The other end of the shaft 28 extends outwardly of the gear housing through a face plate 31 which closes the open face of the gear housing.

Preferably the face plate 31 carries a gasket arrangement for preventing the escape of lubrication from the housing, which gasket also serves as a bearing for the outwardly extending end of the shaft 28. As shown in Fig. 3, a sleeve 32 is secured to the face plate in any suitable manner, as by bending the margin of the plate about the aperture through which the shaft 28 extends inwardly to form a flange 33 to which the sleeve 32 is soldered or welded.

The sleeve 32 is of such thickness that it extends between the face plate 31 and the adjacent face of the worm wheel 27, and the external periphery of the sleeve adjacent the worm wheel is rabbeted, as at 34. The recess thus designated by the groove 34, the flange 33, and the adjacent face of the worm wheel 27 contains a quantity of packing material 35 to prevent the escape of lubrication from the housing.

Externally of the housing the shaft 28 carries a crank 36, which preferably is in the form of a disk having a crank pin 37 rigidly mounted adjacent the periphery thereof. The crank pin 37 engages one end of a link 38, which is secured thereto for relative rotative movement by such means as a pair of pins 39 (Fig. 2) extending through the link 38 on either side of the crank pin 37 into engagement with an annular groove 40 (Fig. 3) in the crank pin.

In Figs. 1, 2, and 4 the means for connecting the crank 36 and the casing 11 is shown, whereby the rotary movement of the crank is translated into reciprocatory movement of the casing. An annular ring 41 loosely encircles a narrow portion of the outer end of the frame section 10^b and is releasably secured to the inner wall of the casing by such means as screws 42. The annular ring 41 carries a shaft 43 extending transversely of the casing and positioned to receive the free end of the link 38, displacement of which, axially of the shaft 43, may be prevented by means of a pair of pins through the shaft on either side of the link. It will be apparent, therefore, that the motor rotates the crank 36 through the intermediate driving connections of the worm 26 and worm wheel 27 and shaft 28, and the crank in turn imparts a reciprocatory movement of the casing 11 axially of the de-

vice by means of the link 38, shaft 43, and annular ring 41.

In order to lessen the force of any vibratory impulses which may be imparted to the 5 armature shaft of the motor, a thrust bearing is preferably provided for the end of the armature shaft in the gear housing. A simple form of bearing is shown in Fig. 1 as comprising a stud 44 having a screw threaded engagement with the gear housing, and extending thereinto in axial alinement with the armature shaft 22. Opposed recesses in the adjacent ends of the armature shaft 22 and the stud 44 receive a bearing ball 45. Adjustment 10 of the stud 44, relative to the armature shaft 22, is maintained by means of a lock nut 46 on the outer end of the stud.

Means may be provided for preventing 20 relative rotation between the casing 11, as represented by the annular ring 41, and the frame. Referring to Figs. 1 and 4, such a means is shown as comprising a short pin 47 having a screw threaded engagement with the ring 41 and extending inwardly of the 25 center thereof into engagement with a slot 48 formed in an adjacent portion of the frame section 10^b. Preferably the pin 47 carries an anti-friction roller 49 thereon.

The general appearance of the device simulates quite closely that of an ordinary rolling pin, and in the operation and use of the device it is applied to the body parts in substantially the same manner as a rolling pin would be handled. Thus, both hands grasp 35 the handles 19 and the casing is pressed against any part of the body, thereby imparting the vibratory movement of the casing to the body. Inasmuch as the vibratory strokes are rapid and powerful, the entire 40 mass of body tissue underlying the part engaged by the casing will be thoroughly massaged and stimulated. Consequently, by moving the casing more or less rapidly across the body, large areas thereof may be very 45 easily treated.

During the passage of the machine across the body surface, the casing may be caused to slide relative to the body surface or, without interfering with the operation of the machine, 50 the handles may be allowed to turn in the user's hands so that the casing rolls across the engaged surface. It is contemplated, however, that the user may hold the handles firmly and yet allow the casing to roll across 55 the body. To this end, the handles 19 may be loosely mounted in a well known manner upon the shanks of the bolts 18 for rotational movement relative thereto. For the same purpose relative rotation between 60 the casing and the frame assembly may be permitted. Thus, as shown in Fig. 5, the ring 41 instead of being rigidly secured to the casing, by means of the screws 42, is provided with an annular groove 50 in the peripheral 65 surface thereof adjacent the inner wall of

the casing. The groove is engaged by a series of short studs 51 extending inwardly from and rigid with the casing. Consequently, the reciprocation of the ring by the crank 36 will be translated to the casing through the engagement of the groove 50 and studs 51, while the casing rotates with respect to the frame.

In addition to the vibratory effect which is produced by the direct application of the casing to the body, the machine is capable of producing body vibrations of a different character which are particularly beneficial to the muscles in the upper part of the body. In this use of the machine, the operator 70 grasps the casing 11 at about its middle and holds the machine at arm's-length from the body. The vibratory strokes of the relatively heavy inner section of the machine in this position have sufficient power to produce vibration in the operator's arms, which is transmitted throughout the muscles in the upper 75 part of the body. By changing the angular position of the machine relative to the body 80 the operator may also change the character 85 of the vibrations produced in the muscles.

While the invention is susceptible of various modifications and alternative constructions, I have shown in the drawing and have herein described in detail the preferred embodiment, but it is to be understood that I do not thereby intend to limit the invention to the specific form disclosed, but intend to cover all modifications and alternative constructions falling within the spirit and scope 90 of the invention as expressed in the appended claims.

I claim as my invention:

1. An exercising and massaging device comprising, in combination, a two part elongated frame, means for securing said parts together to form a single unit, an electric motor mounted in one part of said frame, a crank mounted in the other part of said frame, a worm and worm gear connection between said motor and said crank, a tubular casing enclosing said frame and capable of axial sliding movement relative thereto, an end closure for each end of said casing, said closures being mounted rigidly with the ends of said frame and arranged to slide within the ends of said casing, handles extending axially outwardly from said end closures, a ring member rigidly secured within said casing for movement therewith, a link connecting said crank and said ring member whereby driven movement of said crank effects a reciprocating movement of said casing relative to said frame and end closures, and a pin and slot connection between said frame and ring member to prevent relative rotative movement between said casing and frame.

2. A portable exerciser and massaging device comprising, in combination, an elongated frame, a motor mounted in said frame, a

crank mounted in said frame, driving connections between said motor and crank, hand pieces for an operator secured rigidly to said frame at either end thereof, a tubular member enclosing said frame and adapted for axial sliding movement relative thereto, and driving connections between said crank and said member for translating the rotary motion of said crank into rapid reciprocatory movement of said member.

3. A portable exercising and massaging device comprising, in combination, a hollow casing, an electric motor mounted within said casing, said motor and casing having relative movement one to the other axially of the casing, and driving connections between said motor and said casing for producing such movement in rapid reciprocatory strokes.

20 4. A portable exerciser and massaging device comprising, in combination, an elongated casing, means at opposite ends thereof for supporting said casing in a user's hands, said casing and said supporting means being arranged for movement relative to each other in a direction longitudinally of said casing, and driving means for producing such relative movement in the form of rapid reciprocatory strokes.

30 5. A portable exerciser and massaging device comprising, in combination, a casing, means for supporting said casing in a user's hand and arranged to permit relative movement between said casing and said means, and driving means for producing a relative reciprocatory movement between said casing and said supporting means, said supporting means being of substantially greater weight than said casing so that the major portion of said reciprocatory movement is by said casing.

In testimony whereof, I have hereunto affixed my signature.

IRVEN H. WILSEY.
